CLAIM

The ornamental design for a case for containing items used by engineers, architects and the like, substantially as shown and described.

DESCRIPTION

FIG. 1 is a perspective view of a case for containing items used by engineers, architects and the like, showing my new design;

FIG. 2 is a left side perspective view thereof;

FIG. 3 is a rear perspective view thereof; and

FIG. 4 is a top plan view thereof, the bottom being plain and unornamented.

FIG. 1.

FIG. 2.

FIG.3.

FIG.4.
